UNITED STATES PATENT OFFICE.

J. WALTER SPALDING, OF NEW YORK, N. Y., ASSIGNOR TO A. G. SPALDING & BROTHERS, OF CHICAGO, ILLINOIS.

DESIGN FOR THE ORNAMENTATION OF GAME-TABLETS.

SPECIFICATION forming part of Design No. 18,412, dated June 26, 1868.

Application filed January 12, 1868. Serial No. 260,580. Term of patent 7 years.

To all whom it may concern:

Be it known that I, J. WALTER SPALDING, a citizen of the United States, and a resident of the city, county, and State of New York, have invented and produced a new and original Design for the Surface Ornamentation of Game-Tablets, of which the following is a specification, reference being had to the accompanying drawing, forming part thereof.

- 10 The present design is particularly adapted to the surface ornamentation of game-tablets of any suitable forms or materials, and in the accompanying illustration is illustrated in connection with a circular tablet.
- 15 The design as thus embodied has for its essential characteristic or leading feature a representation of a hunting scene. As therein delineated it consists of a hound, a fallen tree or log, and foliage in the background. As

shown, the hound has one of its fore legs upon 20 the log, with the other fore leg uplifted. The whole may be inclosed by a suitable border or not, as fancy may dictate.

What I claim is—

The design for the surface ornamentation of 25 game-tablets, the same consisting of the representations of a hound and a log, the hound "pointing" over the log, and foliage in the background, substantially as shown and described.

In testimony whereof I have signed my name to this specification in the presence of two subscribing witnesses.

J. WALTER SPALDING.

Witnesses:

W. T. SIMPSON,
J. W. CURTISS.
